WINDOW LATCH

Elias H. Nabham, Brooklyn, N. Y.

Application June 28, 1938, Serial No. 216,219

1 Claim. (Cl. 292—114)

This invention relates to window sash latches, and aims to provide a positively operating locking means which should be jimmy-proof and otherwise entirely safe from being opened from the outside.

The above and other objects will become apparent in the description below, in which similar characters of reference refer to like-named parts in the accompanying drawing.

10 Referring briefly to the drawing,

Figure 1 is a front elevational view of a window, illustrating the application of the latch.

Figure 2 is a cross-sectional view taken on the line 2—2 of Figure 1.

15 Figure 3 is a plan view of the latch per se partly in section, taken on the line 3—3 of Figure 2.

Figure 4 is a cross-sectional view, taken on the line 4—4 of Figure 3.

Figure 5 is a fragmentary view taken on the 20 line 5—5 of Figure 3.

Referring in detail to the drawing, the numeral 10 represents a roof-like housing secured by means of ears 11 to the top ledge of the lower window sash 12. On the bottom ledge of the 25 upper sash 13, a keeper 14 is similarly secured.

The front wall 15 of the housing 10 is provided with an opening or slot 16 near the top thereof, and the rear wall 17 is likewise provided with a wider opening or slot 18 intermediate its height.

30 A bolt 19 is freely movable, both longitudinally and vertically, through the opening 18, and on its end which protrudes from the housing an upwardly turned hook 20 is formed. On its end within the housing, the bolt 19 has an upwardly

35 turned tongue 21 which is adapted to frictionally contact the roof of the housing. A stud 22 secured to the tongue 21, extends forward through the opening 16, and has its end a handle or grip 23. The stud 22 is freely movable, longitudinally

40 and vertically, in the opening 16. It is to be noted that the bolt and its aligned stud both extend angularly upward from the rear toward the front.

On each side of the bolt 19, a stem 24 is 45 anchored at its rear end in the wall 17 in the fashion of a rivet, in such position that it also extends angularly upward toward the front at the substantially same angle as the bolt 19. Ears

25 extend from the sides of the tongue 21, and the 50 forward ends of the pins 24 extend slidably through openings 27 through the ears 25. The openings 27 are of a sufficiently greater diameter than the pins 24 to permit vertical movement (Figure 5) of the pins 24 within the openings 27.

55 These pins have heads 26 on their forward ends

to serve as limit stops with respect to longitudinal movement therealong of the ears 25. Each pin 24 is surrounded, between its ear 25 and the rear wall 17, by a helical expansion spring 28 which normally urges the ears 25, and hence the 5 tongue 21, stud 22 and handle 23, forward. Because of the upward inclination of the pins 24 in a forward direction, the normal position of the tongue 21 is to lie frictionally against the roof of the housing and that of the stud 22 is to lie against 10 the lower edge of the opening 16.

Figures 3 and 4 show the latch in extended operative position. To release the latch, the handle 23 is pushed upward. As this is done, the top edge of the tongue 21 will first strike the roof 15 of the housing, and will then serve as a pivot about which the stud 22 rises further and about which the rear end of the bolt 19, and hence the hook 20, are depressed, until the hook 20 has been lowered to a position clear of the keeper 14. Then 20 the handle 23 is released, and the pressure of the springs 28 will force the bolt 19, and all of the above-mentioned parts rigid therewith, forward until the ears 25 reach the pin heads 26, which will occur at the same time as the hook 20 has 25 reached the space between the rear wall 17 and the keeper 14. The springs 28 therefore serve to retain the bolt 19 in unlatched position. When it is desired to latch the window, the handle 23 is simply pushed home toward the rear, and 30 when in its extreme position, in which the hook 20 will have gone beyond the keeper 14, the handle is depressed, thus raising the hook 20 into its maximum elevated position, and the handle is released. The springs 28 then again urge the bolt 35 forward, but since the hook 20 is now on a level to engage the keeper in its forward travel, it will be stopped by the keeper in the position shown in Figure 4, and the springs 28 will serve to retain the bolt in extended and latched position. It is 40 obvious from the above that the bolt in latched position will be secured against tampering, and that the operation of the device to latch or unlatch a window is simple and speedy.

Obviously, modifications in form and structure 45 may be made without departing from the spirit and scope of the invention.

I claim:

A window latch comprising a housing and having an opening in its front wall and opening in 50 its rear wall, a bolt slidably mounted therein at an angle to the horizontal, said bolt passing through said openings, said openings being relatively large to permit vertical movement of said bolt therein, a tongue on said bolt intermediate 55

its length within said housing and extending upward toward the roof of the housing, guide pins secured in the rear wall of said housing and extending forward therein at substantially the same angle as said bolt, ears on said tongue having openings therethrough, said pins passing through said openings, coiled expansion springs surrounding said pins between said rear wall and said ears, heads on the free ends of said pins within the housing, said bolt having an upturned hook on its rear end for engaging a keeper comprising an inverted U-shaped member, said hook engaging the rear of said keeper in latched position and

said springs in said latched position normally urging said hook to remain in said latched position, elevation of the front end of said bolt causing said tongue to strike the roof of said housing, continued elevation of said front end of said bolt causing said bolt to swing about the point of contact between said tongue and roof as a pivot and to lower said hook out of engagement with said keeper, said springs thereupon serving to urge said bolt and said hook thereon forward to a position clear of said keeper. 5 10

ELIAS H. NABHAM.
